W. H. SCULLY

PERCUSSION TOOL

Filed April 4, 1922

Patented June 9, 1925.

1,540,868

UNITED STATES PATENT OFFICE.

WALTER H. SCULLY, OF FLORENCE, NEW JERSEY.

PERCUSSION TOOL.

Application filed April 4, 1922. Serial No. 549,506.

To all whom it may concern:

Be it known that I, WALTER SCULLY, a citizen of the United States, and a resident of Florence, in the county of Burlington and 5 State of New Jersey, have invented certain new and useful Improvements in Percussion Tools, of which the following is a specification.

This invention relates to improvements 10 in percussion tools adapted to be operated by compressed air or other motive fluid and more particularly relates to an improvement in pneumatic drills, hammers or the like.

The object of the invention is to provide 15 an improvement of this character in which the percussion tool proper may be readily adjusted angularly without disassociating it from the other elements of the organization.

Another object is to provide a percussion 20 tool of this character which may be conveniently manipulated and which does not subject the operator to all of the shocks incident to the drilling or hammering operation, the major portion of such shocks being 25 taken up and absorbed and not being transmitted to the handle portion of the tool.

Another object is to provide an improvement 30 of this character which is of simple and durable construction, reliable in operation, and easy and inexpensive to manufacture and apply.

Other objects and advantages of the invention reside in certain novel features of 35 construction, combination and arrangement of parts which will be hereinafter more fully described and particularly pointed out in the appended claims, reference being had to the accompanying drawings forming part of 40 this specification, and in which:

Figure 1 is a view in perspective, illustrating one embodiment of the invention;

Figure 2 is a view thereof in longitudinal section, parts being shown in elevation for 45 the sake of illustration;

Figure 3 is a group view, illustrating respectively the parts of the invention prior to assembly;

Figure 4 is a detail view of the bushing, 50 showing the same in vertical section.

Referring to the drawings wherein for the sake of illustration is shown the preferred embodiment of the invention, the numeral 10 designates generally a percussion tool which may be of any type and which preferably embodies a cylinder 11 having a

handle 12 at one end and having a piston or hammer 13 operating therein. The piston or hammer 13 is operated by the action of compressed fluid in the usual manner and 60 serves to impart percussion movement to the percussion tool to be hereinafter more fully described. The arrangement may be valveless or any suitable system of fluid distribution may be utilized. However, the 65 particular means for imparting percussive movement to the tool of itself constitutes no part of the present invention and the various types of well known mechanism utilized for this purpose have been adverted to 70 merely for the sake of illustration.

A tubular handle 15 is connected with the cylinder 11 and is milled, as at 16, to facilitate assembly and disassembly thereof with the cylinder. A bushing 17 is inserted in 75 the handle and is held therein by frictional engagement, the bushing having a driving fit in the handle 15. A portion of the bore of the bushing is cylindrical, as at 18, and a portion is of polygonal formation, as at 19. A percussion tool designated generally at 20 such as a drill, chisel, hammer or the like is provided and includes a shank 21 having a portion 22 of circular formation adapted to operate in the portion 18 of the 80 bushing of corresponding formation and the shank 21 also includes a portion 23 of polygonal formation and adapted to operate in the section 19 of the bushing. A sleeve 25 is arranged on the shank 21 of the tool 20 85 and is provided at its inner end with an annular flange 26, the sleeve and the annular flange being accommodated in a counterbore 15^a provided at the outer end of the tubular handle 15. The outer end of the sleeve 25 90 has secured thereto a collar 27, the periphery of which is milled, as at 28. Common means is employed for securing the collar 27 to the sleeve 25 and for securing the sleeve 25 to the shank 21 of the tool, and this means 95 preferably comprises a set screw 29 having threaded engagement with radial openings provided therefor in the sleeve and collar and having its inner end received in a depression provided therefor in the shank 21 100 of the drill.

A coil spring 30 is arranged on the sleeve 25 within the counterbore 15^a one end of the coil spring abutting the flange 26 of the sleeve. The other end of the spring 30 110 abuts an annular plug or ring 31 having screw threaded engagement with the outer

end of the handle 15 and having snug working fit with the sleeve 25. The spring 30 is tensioned to resist outward movement of the tool 20 since when the tool moves outwardly it carries the sleeve 25 with it and since this movement of the sleeve tends to increase the tension or further compress the coil spring 30, and this action being opposed by the resiliency of the spring. The 10 stroke of the percussion tool 20 is not sufficient to carry the polygonally formed portion 23 of the shank of the tool out of the section 19 of the bushing that is out of the section which is of polygonal formation so that during normal operation of the tool it is reciprocated back and forth without changing its angular relation with respect to the handle 15. This angular relation may be changed by grasping the shank 21 20 of the tool 20 and pulling it outwardly against the tension of the spring 30 until the portion 23 has been drawn out from the socket 19 at which time the tool may be rotated to vary its angular relation with respect to the handle 15. Thus the character of the drilling or hammering operation may be varied without necessity of the operator assuming strained and abnormal positions. Again, it is not necessary for the operator 30 to directly grip the shank 21 of the tool as the handle 15 obviates this. Moreover, the shocks received by the tool 20 and shank 21 are not transmitted to the handle in view of the interposition of the spring 30.

35 It is to be understood that the tension of the spring 30 is sufficient to prevent the polygonally formed portion of the shank from being displaced from the bushing and since the spring thus retains the tool in place 40 the operator may grasp the barrel of the tool and it is not necessary for him to hold the tool and the operator is thus relieved from shocks and strains to which he might otherwise be subjected if it were necessary 45 for him to directly grasp the shank of the tool.

I claim:

1. In a percussion tool, a tubular handle, a bushing inserted in said handle and having a portion of polygonal formation and constituting a socket, a percussion tool having a shank including a portion of polygonal formation operating in said socket, and a spring connected with the shank and 50 cooperating with the tubular handle for cushioning the handle and for constraining the polygonal portion of the shank to movement in the socket during its working stroke

and return movement but permitting the same to be withdrawn manually from the 60 socket to angularly adjust the tool relative to the handle.

2. In a device of the character described, a tubular handle, a bushing inserted in said handle and having a portion of polygonal 65 formation and constituting a socket, a percussion tool having a shank including a portion of polygonal formation operating in said socket, said handle having a counterbore at its outer end, a sleeve arranged on 70 the shank of the tool and operating in said counterbore, said sleeve being secured to the shank of the tool, and a coil spring arranged on the sleeve within the counterbore and associated with the sleeve and with the 75 tubular handle to normally restrain the polygonal portion of the shank of the tool to operate in the socket while permitting the same to be withdrawn from the socket and angularly adjusted.

3. In a device of the character described, a tubular handle, a bushing inserted in said handle and having a portion of polygonal formation and constituting a socket, a percussion tool having a shank including a portion of polygonal formation operating in said socket, said handle having a counterbore at its outer end, a sleeve arranged on the shank of the tool and operating in said counterbore and having an annular flange 80 at its inner end, a collar arranged on the outer end of said sleeve, a set screw for securing the collar and the sleeve to the shank of the tool, a coil spring arranged on the sleeve within the counterbore and 85 abutting the annular flange at its inner end and an annular cap having threaded connection with the outer end of the handle and serving as an abutment for the outer end of said spring.

4. In a device of the character described, a tubular handle having a socket or polygonal formation, a tool having a shank provided with a portion of corresponding formation operating in the socket, and yieldable means connected with the shank and cooperating with the tubular handle for cushioning the handle and for constraining the polygonal portion of the shank to move in a socket during its working stroke and return movement but permitting the same to be withdrawn manually from the socket to angularly adjust the tool relative to the handle.

WALTER H. SCULLY.
